United States Patent Office

Des. 214,171
Patented May 20, 1969

214,171

VASE OR SIMILAR ARTICLE

Lena L. Troutman, 418 W. Monroe,
Salisbury, N.C. 28144

Filed July 5, 1968, Ser. No. 12,636

Term of patent 14 years

Int. Cl. D11—02

U.S. Cl. D29—28

FIG. 2 is a top plan view thereof,

FIG. 3 is a side elevational view looking in the direction of arrows 3—3 of FIG. 1,

FIG. 4 is a side elevational view looking in the direction of arrow 4—4 of FIG. 1, and

FIG. 5 is a sectional view taken on line 5—5 of FIG. 1.

I claim:

The ornamental design for a vase or similar article, substantially as shown.
